WELL BAILER

Weldon C. Erwin and Cecil H. Sweet, Brea, Calif.,
assignors to John Grant, Los Angeles, Calif.

Application April 22, 1933, Serial No. 667,439

17 Claims. (Cl. 166—19)

This invention has to do generally with improvements and features of construction applicable to tools or devices such as are used in cleaning wells, and in accordance with the broader principles of the invention it is applicable to well cleaners, such for example, as we set forth in our copending application entitled Well tool, Serial No. 648,072, filed December 20, 1932, as well as to that type or form of tool ordinarily termed "bailer." Throughout the following presentation of our present invention, we will refer to it as applied to or embodying a bailer, it being understood that such reference is not to be construed as limiting the scope or range of application of the invention, but that the invention is broadly applicable to well tools, and particularly bailers or devices of the type set forth in our above mentioned copending application.

It is a general object of this invention to provide a well bailer, or the like, which is simple and inexpensive of construction, dependable, and effective in operation. The tool of this invention includes few simple parts formed and related, so that they can be readily manufactured and assembled, and the working or functioning parts of the device are such as to be particularly effective and dependable in operation.

It is a general object and feature of our invention to provide a well device of the character mentioned in which the body or cavity of the device is closed by a frangible closure or sealing disc adapted to be operated or broken by a punch, which punch is effective and dependable in operation, and is such that it does not materially interfere with the free flow or entrance of material into the device when the closure is broken.

Another object of our invention is to provide a simple, practical and improved construction to facilitate unloading or emptying of the device after it has been removed from the well.

It is another object of our invention to provide a well tool of the character described with a lateral discharge opening close to the lower end of the material carrying chamber of the device, which opening is provided with an effective closure that can be readily applied and removed in the course of handling or manipulating the tool.

It is a further object of our invention to provide improvements in a tool of the character mentioned by which the pressures between the interior and exterior of the tool are governed or handled to make the tool safe and simple and rapid to operate.

A particular object of the present invention is to provide means in connection with the body of a

tool of the character described by which pressure is admitted into the body above the material in the body as the material is unloaded or discharged from the body in order to prevent a negative or reduced pressure occurring in the body above the material being discharged, such as might retard or prevent the discharge of material from the body.

Another object of this invention is to provide a novel and improved means for mounting a closure or sealing disc in a tool of the character mentioned. By the present invention we provide a mounting for the closure disc by which it is possible for an operator to quickly and effectively apply and remove a closure disc without disassembling or otherwise manipulating the major or principal parts of the device.

The various objects and features of the present invention will be best and more fully understood from the following detailed description of a typical form and application of the invention, throughout which description reference is had to the accompanying drawings showing the invention applied to a well bailer, in which drawings:

Fig. 1 is a longitudinal detailed sectional view of the upper portion of a bailer embodying features of the present invention.

Fig. 2 is a longitudinal detailed sectional view of the lower portion of the bailer showing features provided by our present invention.

Fig. 3 is an enlarged detailed transverse sectional view taken as indicated by line 3—3 on Fig. 2.

Fig. 4 is an enlarged detailed transverse sectional view taken as indicated by line 4—4 on Fig. 2.

Fig. 5 is an enlarged detailed transverse sectional view taken as indicated by line 5—5 on Fig. 2.

Fig. 6 is an enlarged side elevation of a portion of the tool, being a view taken substantially as indicated on line 6—6 on Fig. 2.

Fig. 7 is a view of the parts shown on Fig. 6 taken as indicated by line 7—7 on Fig. 6.

The various features of construction provided by our present invention are disclosed in or as applied to a well bailer adapted to be run or lowered into a well to remove material from the well. The present invention relates to features applicable to a bailer, well cleaner, or similar tool, in which the loading or action of the tool is effected by the hydrostatic head of fluid in the well. Bailers operated on this principle are commonly termed "vacuum type bailers". This type of bailer, or like tool, includes a body or chamber

member which is empty as the tool is lowered into the well, and is sealed to prevent fluid in the well from entering it. When the tool has been lowered to the desired point in the well, 5 the seal or closure means is operated so that the head of fluid in the well, which is obviously much greater than the pressure of the air trapped in the tool when it was sealed at the surface of the well, causes fluid or material in the well to 10 rapidly enter or fill into the tool until the internal and external pressures equalize. By this action the tool is loaded or filled in the well at or under the pressure existing in the well at the point the tool is operated.

15 The bailer embodying the present invention and illustrated in the accompanying drawings includes, generally, a body A, a closure means B that operates to close or seal the lower end of the body, means C for operating or opening the 20 closure, a check valve D for retaining material in the body after it has entered the body, control means E in connection with the body to allow fluid to escape from the body so that excessive pressures do not occur within the body when 25 the tool is removed from the well, control means F for admitting pressure into the body as the body is being emptied to prevent a negative or reduced pressure from developing in the body, and various other features, the details and functions 30 of which will be hereinafter described.

The body A is an elongate tubular element or structure forming a container or chamber adapted to receive material in a well, and to carry it out of the well. The body A further 35 forms a carrying or mounting for the various elements of the device, and thus becomes the principal element of the tool. In the preferred form of construction the body is sectional, for instance, it may be formed of a main section 10, a 40 top section 11 applied to the upper end of the main section, and a bottom section 12 applied to the lower end of the main section. The main section 10 of the body forms the principal material receiving chamber of the device, and in practice 45 is a comparatively long tubular section formed of pipe or tubing sufficiently heavy to withstand the pressures under which the tool has to operate.

50 The top section 11 of the body is applied to the upper end of the main section 10 to close it, and acts as a coupling or means for connecting the device with an operating member such as a string of pipe or a suitable line. In the drawings we have shown the top section 11 screw 55 threaded to the upper end of the main section 10, and provided at its upper end with a tapered screw threaded pin projection 13 adapted to receive a coupling, rope socket, or the like. In accordance with the preferred form of the invention, the top section 11 is employed as a mounting or carrier for the means E and F hereinafter described.

The bottom section 12 of the body A is a tubular section connected to the lower end of the main section 10 through a suitable screw threaded connection. The bottom section 12 in the construction illustrated carries the check valve D, is provided with a lateral discharge opening 14 65 above the valve D, and is adapted to receive and carry the mounting member 15 which supports the closure means B. The section 12 is a tubular part sufficiently long to accommodate the other parts above mentioned. The upper end of the section 12 is provided with a central screw 70

75 threaded socket 16 that receives the threaded lower end of the main section 10 of the body.

An eccentric opening 17 extends downwardly through the section 12 from the socket 16 to the centrally located chamber 18, which accommodates the valve D. The opening 17 through the body section 12 being eccentric as clearly illustrated in Figs. 2, 3 and 7 of the drawings, provides a thick wall portion 19 at one side of the body where the opening 17 extends through 10 the body, providing stock or material to accommodate the discharge opening 14 and its closure, as will be hereinafter described.

A reduced opening 20 continues downwardly from the lower end of the valve chamber 18 to 15 the lower end of the body section 12. The differential in size between the opening 20 and the valve chamber 18 results in the formation of a valve seat 21 facing upwardly in the body section 12 to receive the check valve D. Check valve D 20 is preferably a ball valve adapted to cooperate with the seat 21 as illustrated in Fig. 2 of the drawings. The valve is adapted to be lowered into position in the chamber 18 through the opening 17, and is held against displacement from 25 the chamber by a retaining bar 22 arranged through the upper end portion of the valve chamber, as shown throughout the drawings.

The discharge opening 14 provided by our invention extends laterally through the thickened 30 or heavy wall portion 19 of the body section 12 to communicate with the opening 17. The opening 14 is preferably made of substantially the same diameter as the opening 17, as will be apparent from a consideration of the drawings. 35 The closure 24 is provided to normally close the discharge opening 14 and has a plug portion 25 adapted to project into the opening 14, and a flange portion 26 presenting a face 27 that engages or abuts the flat face 28 provided at the 40 outer end of the opening 14. The flange 26 has diametrically opposite ear portions 30 adapted to engage under overhanging lugs 31 formed by transversely notching the thickened wall portion 19 of the body section 12 immediately outward 45 of the face 28, providing transverse ways 35 in Figs. 2 and 6 of the drawings. The outer end or exterior surface 36 of the closure 24 is shaped so that when the closure is in position with the ears 30 held by the lugs 31 as shown in Figs. 2 50 and 6, it extends longitudinally parallel with the exterior of the body section 12, and is laterally curved concentric with the outer surface of the body section 12, as clearly shown throughout the drawings. The outer portion of the closure 24 55 that fits between the lugs 31 is turned concentric with the opening 14 to a size or diameter that will fit between the lugs 31 as shown in Fig. 6. This turned portion of the closure is designated by numeral 31.

With the discharge opening and the closure therefor formed and related as just described and as shown throughout the drawings, the closure can be arranged so that the plug portion 25 enters the opening 14 when the ears 30 are in line 65 transversely of the tool. From this position the closure can be rotated 90° to bring the ears 30 into position behind the lugs 31, in which position the closure is held against displacement from the body section 12. For the purpose of making 70 the closure 24 tight, a suitable packing ring or gasket 38 may be arranged in a suitable groove provided at the junction of the plug portion 25 and the flange 26, and clamp screws 39 may be provided in the lugs 31 to be tightened against 75

the flanges 30 so that the closure is held tight against the face 28.

The mounting member 15 for the closure B is a tubular part projecting downwardly from the lower end of the body section 12 so that it is in effect a continuation of the body section 12. In the particular construction illustrated the part 15 is formed separate from the body section 12, and is attached thereto by a suitable threaded connection 40. An opening 41 extends longitudinally through the mounting member 15, and has a portion 41a of reduced diameter at its upper end or immediately adjacent connection 40. A seat member or bushing 42 is mounted in the upper end portion of the opening 41a to receive a closure disc 43. In accordance with the present invention, an opening 44 is formed transversely through the mounting member 15 to intersect the opening 41a immediately below the seat 42. The opening 44 is preferably rectangular in cross section with its major dimension transverse of the tool, and somewhat greater than the diameter of the opening 41a. A disc carrier 45 slidably fits the opening 44, and when in position in the opening 44 its ends 45 are flush with and coincide with the curvature of the exterior of the member 15, as clearly shown in Fig. 4 of the drawings.

An opening 46 is formed vertically through the carrier 45 to coincide with the opening through the seat 42 when the carrier is in position in the tool as shown in Figs. 2 and 4 of the drawings. The closure disc 43, which may be formed of any frangible material such as glass, bakelite, or other such composition or material, is mounted in the upper end of the opening 46, formed through the carrier 45, and is adapted to set against the bottom or lower end of the seat 42 when the tool is in operation or conditioned for lowering into a well. In the preferred construction the closure disc 43 is made concavo-convex as shown in the drawings, and is mounted with its convex side facing downwardly. The carrier 43 may be set in position in the opening 44 in any suitable manner. For instance, a set screw 50 may be arranged in the member 15 transversely of the opening 44 to engage and set the carrier 45 as shown in Figs. 2, 4 and 7 of the drawings.

The means C for operating or opening the closure is carried by the lower portion of the mounting member 15 so that it is below the closure disc 43. The closure 43 being in the nature of a frangible disc, the means C is in the nature of a punch adapted to engage or break the disc. The punch, as shown throughout the drawings, includes a tubular stem 60 slidably fitting the opening 41 in the mounting member 15, and a head 61 on the upper end of the stem adapted to engage and to rupture the disc 43. The head 61 is proportioned and shaped to effectively fracture the disc 43, and is mounted or carried on the upper end of the stem 60 through shaped ribs 62, which leave openings 63 providing free communication between the opening 64 through the stem 60, and the interior of the member 15 above the punch.

In practice, the punch may be retained in connection with the mounting member 15 in any suitable manner, for instance, it may be connected to the member 15 for suitable limited longitudinal movement relative thereto by a pin 70 carried by the member 15 to extend through longitudinal slots 71 provided in the stem 60 as clearly shown in Fig. 2. It will be obvious that this forms a simple, secure means of connecting the punch and

member 15, and that the desired movement of the punch relative to the member 15 can be had by suitably proportioned slots 71. The lower end portion of the stem 60 is provided with a foot portion 80, having a plurality of transverse openings 81, as well as a central opening 82 extending through it and communicating with the opening 64 in the stem 60. The foot 80 is threaded to the lower end of the stem 60, and a regulating sleeve 85 is retained between the foot and the lower end portion of the stem, as clearly shown in Fig. 2 of the drawings. The sleeve 85 can be positioned so that the openings 81 are open as shown throughout the drawings, or are restricted or closed, as the operator desires. The lower end portion of the mounting member 15 may be provided with threads 86 to facilitate connecting the structure with other parts or devices in the event that the device is to be used in combination with a well cleaner or other like device.

The control E is provided to allow fluid or pressure to escape from the body as the device is removed from the well, so that there is only a limited pressure differential between the inside and outside of the body when the device is removed from the well. When the device is loaded or filled in the well under the head of fluid standing in the well, air or gas trapped in the upper portion of the body A is under a high pressure, i. e., under a pressure corresponding to the pressure in the well. As the tool is withdrawn from the well, the check valve D operates to prevent escape of fluid from the body A, and therefore in the absence of means for escape of pressure from the body, the body would be removed from the well, with its contents under pressure corresponding to that at which it was loaded in the well. The means E is in the nature of an escape opening 87 provided in the top section 11 of the body, and a control valve 88 normally closing the opening under the action of a spring 89. The valve 88 seats inwardly in the opening 87, and therefore acts as a check valve, preventing the admission of fluid into the body through the opening 87, and acts as an escape valve to allow fluid to escape from the body through the opening 87, when the pressure is sufficient to counteract the spring 88. The spring is held against the valve, under the desired pressure by a tubular plug 90 threaded in the outer portion of the opening 87, as shown in Fig. 1.

The means F provided by the present invention is adapted to facilitate unloading the device after it has been removed from the well. When the device has been removed from the well filled with fluid or other material, the contents of the body are under a certain pressure limited by the means F as above described. When the closure 24 for the discharge opening 14 is removed, the pressure on the material in the body causes the material to immediately flow or discharge through the opening 14, and under the initial impulse given the material by the pressure in the body A, the entire contents of the body tends to discharge through the opening 14 in one continuous flow or action. In practice, this tendency is retarded or checked by the fact that as the material discharges from the body a reduced pressure is established in the body above the material therein, which tends to hold, if not completely retard, discharge of material from the body after a certain amount of material has discharged from the body.

The means F provided by our invention is provided to allow free and continuous discharge of

material from the body upon the closure 24 being removed from the opening 14. The means F in its preferred form includes an opening in the upper portion of the body, for instance in the body section 11, designed to admit fluid into the body under control of a plug and a check valve. In the particular construction illustrated, the opening 91 provided in the body section 11 is threaded and carries a fitting or mounting 92, 10 which has an opening 93 through it controlled by a plug 94 and a valve 95. The plug 94 is threaded in an enlargement 96 of the opening 93 at the outer end of the opening, and is provided with an inner end adapted to be positioned 15 to close the opening 93. Suitable ports or passages 97 are provided in the plug to allow free communication of pressure past the plug, and to the opening 93 when the plug has been backed out in the opening 96 so that the opening 93 is 20 uncovered.

The valve 95 is in the nature of a ball check valve operating in a suitable cage 98, and urged by spring 99 to normally set outwardly to close the opening 93. Suitable ports 100 connect the 25 cage 98 to the interior of the body A so that pressure admitted past the valve 95 enters the body.

When the tool is being lowered into the well, the plug 94 is in position or made tight so that it 30 closes the opening 93. When the tool has been operated in the well and withdrawn therefrom, but before the closure 24 is removed from the discharge opening 14, the plug 94 is loosened to admit atmospheric pressure to the opening 93. Upon the closure 24 being removed from the 35 opening 14, the material in the body will flow out through the opening 14, and as soon as sufficient material has discharged from the body to reduce the pressure within the body so that it is less than that outside of the body, the valve 95 40 will open admitting atmospheric pressure into the body above the material therein. The spring 99 is preferably made light and is merely to retain the valve 95 in working position.

From the foregoing description, it is believed 45 that the operation of the device will be fully understood. The structure is lowered into a well to be cleaned or bailed on a string of pipe or on a line, as the operator may desire. The device is lowered into the well with the plug 94 made 50 tight to close the opening 93, with the closure 24 in place in the discharge opening 14, and a sealing disc in position in the carrier 45 to cooperate with the seat 42. When the structure reaches the bottom of the well or an accumulation of 55 solid material in the well, the downward movement of the punch C is retarded so that relative movement occurs between the body A and the punch C, resulting in the disc 43 being ruptured by the head 61 of the punch. Upon the disc 43 60 being ruptured, the hydrostatic head of fluid in the well being considerably greater than the pressure within the body A, there is a sudden and violent rush of material upwardly through the punch past the valve D, and into the body A. When this filling action has ceased, the valve D 65 seats and operates to prevent discharge of any of the caught material from the device.

When the device has been operated it is then removed from the well, whereupon the operator 70 may release the plug 94 and then remove the closure 24 from the discharge opening 14. The pressure under which the material is held in the body A causes it to discharge from the body through the opening 14, and by reason of the admission of atmospheric pressure into the body A

above the discharging material, the discharging operation continues when once started, resulting in effective and thorough discharging of the body. If for any reason it is found that the material has not thoroughly discharged from the body, 5 the plug 94 may be removed from the fitting 92 and a pressure line, such as a line carrying air or water, may be connected in place of the plug 94 so that fluid pressure is applied to the upper end of the body to flush material down through the body and out of the opening 14. To put the tool in condition for a second operation, the plug 94 is made tight, the closure 24 is applied to the opening 14, and the carrier 45 is removed from the body and then replaced, bearing or carrying a new 10 15 closure disc 43. It will be obvious that these operations are all simple, and such that they can be performed rapidly and without complicated or ungainly operations.

Having described only a typical form and application of the invention, we do not wish to limit ourselves to the particular details hereinabove set forth, but wish to reserve to ourselves changes or modifications that may occur to those skilled in the art, and which may fall within the scope of 25 the following claims.

Having described our invention, we claim:

1. A well tool of the character described including, a tubular body closed at its upper end, a closure for the lower end of the body, means for 30 operating the closure, the body having a lateral discharge opening above the closure and a seat at the outer end of the opening, a plug closure for the opening and adapted to engage the seat, and means for holding the last mentioned closure in 35 position at the opening, including spaced lugs on the body engaging projections on said last mentioned closure.

2. A well tool of the character described including, a tubular body closed at its upper end, a 40 closure for the lower end of the body, means for operating the closure, the body having a lateral discharge opening above the closure and a seat at the outer end of the opening, a plug closure for the opening and adapted to engage the seat, 45 and means for holding the last mentioned closure in position at the opening, including diametrically opposite lugs arranged in line longitudinally of the tool and diametrically opposite ears on the 50 last mentioned closure engaged by the lugs.

3. A well tool of the character described including, a tubular body closed at its upper end, a closure for the lower end of the body, means for 55 operating the closure, the body having a lateral discharge opening and a seat at the outer end of the opening, a closure for the opening and adapted to engage the seat, and means for holding the last mentioned closure in position at the opening, including diametrically opposite lugs arranged in line longitudinally of the tool and diametrically opposite ears on the last mentioned closure engaged by the lugs, the outer portion of 60 said last mentioned closure being shaped to conform to and be flush with the exterior of the body when the ears are engaged by the lugs.

4. A well tool of the character described including, a tubular body closed at its upper end, a closure for the lower end of the body, means for 70 operating the closure, the body having a lateral discharge opening, the bore of the body being eccentric to the exterior of the body at the lateral opening and the lateral opening being formed through the thickest portion of the body wall, a closure for the lateral opening, and means for

holding the last mentioned closure in position at the opening.

5. A well tool of the character described including, a tubular body closed at its upper end, a closure for the lower end of the body, an upwardly opening check valve in the body above the closure, and means carried by the body for operating the closure including, a punch having a tubular stem slidably carried by the body and a head 10 on the stem to engage the closure, the lower end of the stem bore being open to well-fluid, and the upper end of the stem bore being adapted to open to the body bore when the closure is opened.

6. A well tool of the character described including, a tubular body having an opening at its upper end and extending from the extension of the body to the bore thereof, said body having a transverse opening at its lower end, a frangible closure for the lower end of the body adapted 20 to be arranged in the body through the transverse opening, means for breaking the closure, a check valve at the lower end of the body to prevent discharge from the body, a discharge opening in the body above the check valve, a closure for the discharge opening, and a control for the opening at the upper end of the body preventing flow outwardly through said opening, and operable to allow flow inwardly through said opening.

7. A well tool of the character described including, a tubular body having an opening at its upper end and a transverse opening at its lower end, a seat in the body at the transverse opening, a frangible sealing disc for the lower end of the body to cooperate with the seat, a carrier for the disc adapted to be arranged in the lateral opening in the body to hold the disc in position to cooperate with the seat, a check valve in the lower part of the body to prevent discharge from the body, a lateral discharge opening in the body including a normally closed check valve above the check valve, a closure for the discharge opening, means for holding said closure in position at the discharge opening, including lugs on the body cooperating with projections on the closure, means for breaking the sealing disc, including a punch having a stem projecting downwardly below the body and shiftable longitudinally relative to the body, and a head at the upper end of the stem for engaging the disc, and a control for the opening at the upper end of the body, including a check valve for preventing flow outwardly through the body and a screw threaded plug arranged in position from the exterior of the body, and adapted to 55 close the opening.

8. In a well tool of the character described, a tubular body member, a transverse opening from the exterior of the body member to the bore thereof, a carrier movable through said opening 60 across the body member bore and supported against displacement axially of the body member by defining walls of the opening, and a frangible closure mounted on said carrier and positioned within the body member bore when 65 the carrier is across said bore.

9. In a tool of the character described, a tubular body member, a downwardly facing seat in the bore, a transverse opening in the wall of the body member, and a closure member for the bore movable therewith through said opening and onto said seat, and means in said opening and engaging the closure to hold it against said seat.

10. In a tool of the character described, a body member having a chamber therein, a relief valve

at the upper end of the chamber opening to the exterior of the body, a frangible closure for the lower end of the chamber, means for breaking said closure and an upwardly opening check valve in the chamber between said relief valve 5 and said closure.

11. In a tool of the character described, a body member having a chamber therein, a relief valve at the upper end of the chamber opening to the exterior of the body, a frangible closure for the lower end of the chamber, means for breaking said closure, an upwardly opening check valve in the chamber between said relief valve and said closure, and a dump valve for the chamber at a point above said check valve.

12. In a tool of the character described, a body member having a chamber therein, a relief valve at the upper end of the chamber opening to the exterior of the body, a closure for the lower end of the chamber, means for opening said closure, and an upwardly opening check valve in the chamber between said relief valve and said closure.

13. In a tool of the character described, a body member having a chamber therein, a relief valve at the upper end of the chamber opening to the exterior of the body, a closure for the lower end of the chamber, means for opening said closure, an upwardly opening check valve in the chamber between said relief valve and said closure, and a dump valve for the chamber at a point above said check valve.

14. In a well tool of the character described, a hollow body, there being a transverse opening through the body wall, an insertable closure for the body-bore near the bottom thereof, and means for mounting the closure in operative position, including a carrier for the closure positioned in said opening.

15. In a well tool of the character described, a hollow body, there being a transverse opening through the body wall, a seat in the body-bore adjacent the opening, an insertable closure for the body-bore at said seat, and a carrier for the closure adapted to be positioned in said opening with the closure in cooperating relation with said seat.

16. A well tool of the character described, including a tubular body closed at its upper end, a closure for the lower end of the body, means for operating the closure, the body having a lateral discharge opening and a seat at the outer end of the opening, there being a transverse way formed in the body, a closure for the opening embodying a plug portion, a flange portion, and a projecting portion, said projecting portion being slidable through said way, said plug portion being enterable in the opening and the flange being engageable with said seat while said projecting portion is entered in said way.

17. A well tool of the character described, including a tubular body closed at its upper end, a closure for the lower end of the body, means for operating the closure, the body having a lateral discharge opening and a seat at the outer end of the opening, there being a transverse way formed in the body adjacent the opening, and a closure for the opening, said last mentioned closure being movable through the way into and out of registration with the opening and being movable 70 radially with respect to the body axis when in such registration.

CERTIFICATE OF CORRECTION.

Patent No. 2,059,629.

November 3, 1936.

WELDON C. ERWIN, ET AL.

It is hereby certified that error appears in the printed specification of the above numbered patent requiring correction as follows: Page 4, second column, lines 32 and 43, claims 1 and 2, strike out the words "above the closure"; page 5, first column, lines 27 and 28, claim 6, for "operable to allow" read a releasable closure for preventing; lines 40 and 41, claim 7, strike out the words "including a normally closed check valve" and insert the same after "body" in line 26, claim 6; and that the said Letters Patent should be read with these corrections therein that the same may conform to the record of the case in the Patent Office.

Signed and sealed this 23rd day of February, A. D. 1937.

(Seal)

Henry Van Arsdale
Acting Commissioner of Patents.
